UNITED STATES PATENT OFFICE

2,273,884

COIL OPENER

Stone Nyberg, Dover, Ohio, assignor to Agnes J.
Reeves Greer, Morgantown, W. Va.

Original application April 29, 1939, Serial No.
270,732. Divided and this application Decem-
ber 27, 1940, Serial No. 371,876

7 Claims. (Cl. 242—78)

The invention relates to apparatus for opening the outer end of a metal coil, so that it may be fed to a recoiler, such for instance as disclosed in Greer Patent No. 2,191,463, dated February 27, 1940, or Greer application Serial No. 230,304, for loosely recoiling the coil so that it may be passed through a pickling machine of the general type disclosed in Greer Patents No. 2,091,921, dated August 31, 1940, and No. 2,196,210 dated April 9, 1940, and the present application is a division of my co-pending application for Coil opener and feeder, Serial No. 270,732, filed April 29, 1939, and relates only to the coil opening mechanism.

Difficulty has been experienced in starting the outer end of a hot rolled coil into recoilers of the general character above referred to, the outer end of the hot rolled coil being loosened or opened up and fed to the recoiler by hand.

The object of the present improvement is to provide a mechanism which will automatically loosen or open up the outer end of the coil and feed the same through a set of leveling or breaker rolls to the recoiler.

Another object is to provide a self-adjusting, fluid cylinder operated spud for loosening or opening the outer end of the coil and bending it outward to proper position to be received in the feeding mechanism.

Another object of the invention is to provide clamping means for holding the coil against movement upon the feed rolls during the operation of the spud.

A still further object is to provide means for rotating the coil after the outer end has been opened up, or loosened, so as to feed said outer end into the recoiler.

The above objects together with others which will be apparent from the drawings and following description, or which may be later referred to, may be attained by constructing the improved coil opener in the manner illustrated in the accompanying drawings, in which—

Figure 1 is a vertical, longitudinal sectional view through the improved coil opening mechanism;

Fig. 2, a transverse sectional view taken as on the line 2—2, Fig. 1;

Fig. 3 a top plan view of the coil opening mechanism; and

Fig. 4, a fragmentary elevation of a portion of the cylinder, which operates the spud, and the bracket which carries the same.

Similar numerals refer to similar parts throughout the several views.

The improved coil opening apparatus to which this application pertains may be mounted in a housing indicated generally at 10, in the lower portion of which are journaled the spaced rolls 11 for supporting the coil C which is to be opened.

A roll 12 is preferably provided in the housing 10 at a point spaced above the rolls 11 and in position to engage one side of the coil, C so as to hold the same positioned upon the rolls 11 while the coil is being unwound.

Sprocket wheels 13 are fixed upon the ends of the rolls 11 and connected by a sprocket chain 14 so that both rolls 11 are driven in the same direction and at the same speed.

For driving the rolls a sprocket wheel 15 may be fixed upon the shaft of one roll 11 and connected as by the sprocket chain 16 with any suitable source of power.

In order to accommodate coils of various widths an adjustable plate 17 may be slidably mounted at one end upon the tie-rod 18 which is located transversely through one side of the housing 10.

The opposite end portion of the plate is adapted to selectively engage any desired notch 19 in the plate 20 located transversely across the other side of the housing.

For the purpose of holding the coil rigidly against movement during the opening operation clamping means is provided comprising the clamping jaw 21 fulcrumed as at 22 at one side of the housing 10 and extending through a slot 23 in the adjacent side of the housing, a lever arm 24 being rigidly connected to said jaw and extending outwardly from the fulcrum and being pivotally connected as at 25 to the piston rod 26 of a fluid operated cylinder 27 which may be hingedly mounted as at 28 upon the adjacent side of the housing 10.

The cylinder 27 may be operated to move the plunger 26 downward or outward in order to withdraw the clamping jaw 21 outwardly through the opening 23 in the housing, in order to place a new coil within the housing, after which the cylinder 27 is operated to the position best shown in Fig. 2, inserting the clamping jaw 21 into the center opening of the coil and pressing said clamping jaw tightly upon the lower portion of the coil to hold the same against movement upon the rolls 11.

A rod 29 may be slidably located through the housing transversely thereof for the purpose of preventing the coil C from lifting out of the housing during the operation of uncoiling the same, when the coil has been unwound to such

a point that the weight thereof will not hold it upon the rolls 11.

This rod may be operated by a fluid cylinder 30 to the piston rod 38 of which is connected the carriage 32, fixed to the outer end of the rod 29, said carriage being provided with rolls 33 rolling upon the guide rods 34 which extend outwardly from the adjacent side of the housing 10 and may be supported at their outer ends as by the bracket 35.

The spud 36 for opening the outer end of the coil may be pivotally mounted as at 37 upon the lower end of the piston rod 38, of an upright fluid cylinder 39, which may be pivotally mounted, intermediate its ends, as indicated at 40, within a bifurcated bracket 41 slidably mounted upon the guide plate 42. This guide plate is transversely located relative to the housing 10 and is connected at its ends to the upper portions of the uprights 43 of said housing. The bracket 41 has guide-ways 44 slidably mounted upon the guide ribs 45 formed upon the guide plate 42.

The upper end of the fluid cylinder 39 is provided with the diametrically opposed studs 46 slidably mounted in the slots 47 of the bifurcated head 48 carried by the end of the piston rod 49 of the fluid cylinder 50 which is pivotally connected as at 51 to the arm 52 carried by the bracket 41.

Springs 53 are connected at opposite ends to the studs 46 and to pins 54 at the forward end of the bifurcated head 48 so as to normally urge the fluid cylinder 39 toward the position shown in full lines in Fig. 1.

A screw shaft 55 is journaled in the uprights 43 adjacent to the guide plate 42 and the internally threaded boss 56 of the bracket 41 is mounted upon said screw shaft, a hand wheel 56a being fixed upon one end of the screw shaft for adjusting the position of the fluid cylinder 39 and spud 36 transversely relative to the housing 10.

In the operation of the improved machine to open the outer end of a coil, a hot rolled coil as indicated at C is placed upon the rolls 11 and the power means operating the sprocket chain 16 is operated to rotate the rolls 11 until the coil assumes the position shown in Figure 1 with the outer end E thereof located as shown in full lines in said figure directly below the normal or inoperative position of the spud 36.

The rotation of the rolls 11 is stopped when the coil reaches this position and the fluid cylinder 21 is operated to move the clamping jaw 21 into the clamping position shown in Fig. 2, clamping the lower portion of the coil against movement on the rolls 11.

In order to facilitate the placing of a coil upon the rolls, the fluid cylinder 50 may have first been operated to swing the cylinder 39 and spud 36 to the broken line position shown at A in Figure 1.

After the coil has been placed in position and clamped as above described, the cylinder 50 is then operated to move the cylinder 39 and spud 36 back to the full line position shown in Figure 1.

With the cylinder 39 in this position the same is operated to force the spud 36 downward beneath the outer end E of the coil loosening said outer end and bending it outward from the coil through the several broken line positions of said outer end indicated in Figure 1, the spud pivotally moving upon the piston rod 38 to accommodate itself to the outward movement of the end of the coil, the spud passing through the

position shown in broken lines at B and finally assuming the broken line position shown at B' in Figure 1.

The spud may then be withdrawn to the full line position of Fig. 1 and the cylinder 21 operated to release the clamping jaw 21 and the sprocket chain 16 is again operated to rotate the rolls 11 rotating the coil in a clock-wise direction as viewed in Figure 1 and the outer opened end 10 E of the coil may be fed into the recoiler and the operation continued until the entire coil is unwound.

When the coil is nearly unwound and becomes so light in weight that its own weight will not hold it down upon the rolls 11 the rod 29 will prevent the coil from lifting out of the housing 10 as the remainder thereof is fed into the recoiler.

I claim:

1. Apparatus for opening the outer end of a coil of metal including rolls for supporting the coil parallel to the rolls, means for rotating the rolls to rotate the coil around its axis, means for clamping the coil against movement upon the rolls, a fluid cylinder pivotally mounted adjacent to the coil, a piston rod in the cylinder movable tangentially toward the coil, an elongated tapered spud pivotally mounted at its larger end upon said piston rod for engaging the smaller end of the spud under and opening up the outer end of the coil, and means for swinging said cylinder upon its pivot to urge the spud against the periphery of the coil.

2. Apparatus for opening the outer end of a coil of metal including rolls for supporting the coil parallel to the rolls, means for rotating the rolls to rotate the coil around its axis, means for clamping the coil against movement upon the rolls, a fluid cylinder pivotally mounted adjacent to the coil, a piston rod in the cylinder movable tangentially toward the coil, an elongated, tapered spud pivotally mounted at its larger end upon said piston rod for engaging the smaller end of the spud under and opening up the outer end of the coil, a second fluid cylinder located at one side of the first named cylinder, and a piston rod in the second cylinder connected to the first cylinder at one side of the pivotal point thereof for swinging the first cylinder upon its pivotal point.

3. Apparatus for opening the outer end of a coil of metal including rolls for supporting the coil parallel to the rolls, means for rotating the rolls to rotate the coil around its axis, means for clamping the coil against movement upon the rolls, a fluid cylinder pivotally mounted adjacent to the coil, a piston rod in the cylinder movable tangentially toward the coil, a spud pivotally mounted upon said piston rod for engaging under and opening up the outer end of the coil, a second fluid cylinder, a piston in said second cylinder operatively connected to said pivotally mounted cylinder for swinging the pivotally mounted cylinder upon its pivot, and spring means associated with the pivotally mounted cylinder and the last named piston rod for swinging the pivotally mounted cylinder upon its pivot to urge said spud against the periphery of the coil.

4. Apparatus for opening the outer end of a coil of metal including a housing, rolls mounted in the housing for supporting the coil parallel to the rolls, means for rotating the rolls to rotate the coil around its axis, means for clamping the coil against movement upon the rolls, a

bracket slidably mounted in the housing for movement longitudinally of the coil, a fluid cylinder pivotally mounted upon the bracket, a piston rod in the cylinder movable tangentially toward the coil, and a spud pivotally mounted upon said piston rod for engaging under and opening up the outer end of the coil.

5. Apparatus for opening the outer end of a coil of metal including a housing, rolls mounted in the housing for supporting the coil parallel to the rolls, means for rotating the rolls to rotate the coil around its axis, means for clamping the coil against movement upon the rolls, a bracket slidably mounted in the housing for movement longitudinally of the coil, a fluid cylinder pivotally mounted upon the bracket, a piston rod in the cylinder movable tangentially toward the coil, a spud pivotally mounted upon said piston rod for engaging under and opening up the outer end of the coil, a second fluid cylinder mounted in the housing, a piston rod in said second cylinder operatively connected to the said pivotally mounted cylinder for swinging the pivotally mounted cylinder upon its pivot, and spring means associated with the pivotally mounted cylinder and the last named piston rod for swinging the pivotally mounted cylinder upon its pivot to urge said spud against the periphery of the coil.

6. Apparatus for opening the outer end of a coil of metal including a housing, rolls mounted in the housing for supporting the coil parallel

to the rolls, means for clamping the coil against movement upon the rolls, a fluid cylinder pivotally mounted adjacent to the coil, a piston rod in the cylinder movable tangentially toward the coil, a spud pivotally mounted upon said piston rod for engaging under and opening up the outer end of the coil, means for releasing the coil clamping means, means for rotating the rolls to rotate the coil around its axis, a rod slidably mounted transversely of the housing, and a second fluid cylinder for slidably moving said rod through the open center of the coil.

7. Apparatus for opening the outer end of a coil of metal including a housing, rolls mounted in the housing for supporting the coil parallel to the rolls, means for clamping the coil against movement upon the rolls, a fluid cylinder pivotally mounted adjacent to the coil, a piston rod in the cylinder movable tangentially toward the coil, a spud pivotally mounted upon said piston rod for engaging under and opening up the outer end of the coil, means for releasing the coil clamping means, means for rotating the rolls to rotate the coil around its axis, a rod in the housing at one side of the coil, a notched bar in the housing at the other side of the coil, and a partition plate having one end portion slidably mounted upon said rod and having its other end portion arranged to selectively engage any notch in said bar.
